REAR CAR OF A RAIL VEHICLE

Filed Feb. 2, 1939

FIG.1

FIG.2

FIG.3

INVENTOR:

John W. Patton

John W. Patton
ATTORNEY

UNITED STATES PATENT OFFICE

126,867

DESIGN FOR A REAR CAR OF A RAIL VEHICLE

John W. Patton, Philadelphia, Pa., assignor to
Edward G. Budd Manufacturing Co., Philadelphia, Pa., a corporation of Pennsylvania

Application February 2, 1939. Serial No. 82,725

Term of patent 14 years

To all whom it may concern:

Be it known that I, John W. Patton, a citizen of the United States, residing at Philadelphia, in the county of Philadelphia and State of Pennsylvania, have invented a new, original, and ornamental Design for a Rear Car of a Rail Vehicle, of which the following is a specification, reference being had to the accompanying drawing, which forms a part thereof.

Figure 1 is a perspective view from the rear showing the rear car of a rail vehicle.

Figures 2 and 3 are a side elevation and plan of the rear portion of the same.

The dominating features of the design are the extension of the vertical side wall of the car a substantial distance above the window openings before it merges into the curvature of the roof, the ornamental beading or corrugation of the vertical extension, and the carrying of this ornamental beading or corrugation above the window openings around the rear end of the car.

I claim:

The ornamental design for a rear car of a rail vehicle, substantially as shown and described.

JOHN W. PATTON.
